(57) **ABSTRACT**

An armored cab having at least an upper wall, two side walls, a front wall, a back wall, and a bottom wall. The armored cab and its respective walls include a longitudinal axis extending from the back wall to the front wall. The bottom wall includes at least one concave surface. The at least one concave surface faces downwardly and away from the armored cab, and is disposed in a direction substantially parallel with the longitudinal axis of the armored cab.

ARMORED CAB FOR VEHICLES

RELATED APPLICATIONS

This application is a continuation of U.S. patent application Ser. No. 13/349,188 filed Jan. 12, 2012, which is a continuation of U.S. patent application Ser. No. 12/272,520 filed Nov. 17, 2008, which claims the benefit of U.S. Provisional Patent Application Ser. No. 61/003,365, filed Nov. 16, 2007, all of which are entitled Armored Cab for Vehicles, and all of which are hereby incorporated by reference herein as if fully set forth in their entirety.

BACKGROUND OF THE INVENTION

1. Field of the Invention

Various types of vehicles, such as joint light tactical vehicles (JLTV), tactical vehicles, or tactical trucks, and similar vehicles used in a battlefield, or other armed conflict situations, may sustain land mine strikes, or attacks from improvised explosive devices (IED), such as roadside bombs. It would be desirable for these vehicles to be able to withstand the forces of the foregoing types of attacks and explosions to enhance the survivability of the occupants of such vehicles. By armoring the cab, or passenger cabin, of a vehicle, the survivability of the occupants of the vehicle may be enhanced.

2. Description of the Related Art

It is often desirable to transport soldiers, non-military personnel, and equipment across hostile territory via motorized land vehicles such as tactical vehicles, tactical trucks, and similar vehicles. During transport, however, people occupying the cab of the vehicle are susceptible to injury from IEDs, land mines, and other bombs and explosives. To reduce injury from these encounters armor plating has been added to the cabs of such vehicles.

Without wishing to be bound by the theory, typically prior vehicle cabs were armored by increasing blast resistance through increased material strength and thickness, as well as increasing blast deflection through the use of angular and "V" shaped structures. Accordingly, the armoring of the foregoing vehicles has been achieved by using thick flat panels, or flat surfaces, of armor plate material for, or upon, the walls of the cabin, or passenger cabin.

SUMMARY OF THE INVENTION

In accordance with one embodiment of the present invention, an armored cab is provided. The cab preferably includes at least an upper wall, two side walls, a front wall, a back wall, and a bottom wall. The armored cab and its respective walls include a longitudinal axis extending from the back wall to the front wall. The bottom wall includes at least one concave surface. The at least one concave surface faces downwardly and away from the armored cab, and is disposed in a direction substantially parallel with the longitudinal axis of the armored cab.

In accordance with another embodiment of the present invention, the bottom wall of the cab further includes at least one convex surface having a convex shape. In a preferable embodiment, the concave surface and the convex surface are disposed in a direction substantially parallel with a longitudinal axis of the armored cab.

In accordance with another embodiment of the present invention, an armored cab is provided. The cab preferably includes at least an upper wall, two side walls, a front wall, a back wall, and a bottom wall. The armored cab and its respec-

2

tive walls include a longitudinal axis extending from the back wall to the front wall. The bottom wall includes, a first and second concave surface, which face downwardly and away from the armored cab, and are disposed in a direction substantially parallel with the longitudinal axis of the armored cab. The first concave surface is disposed in alignment with a forward, or front, portion of a floor of the cab, and the second concave surface is disposed in alignment with a rearward, or rear portion of the floor of the cab. Preferably, the first and second concave surfaces are integral with the bottom wall, and centrally disposed between the at least two side walls. Continuing with the embodiment, the bottom wall further includes a first and second convex surface disposed in the direction substantially parallel with the longitudinal axis of the armored cab. The first convex surface extends along a first lower-most portion of the bottom wall, and the second convex surface extends along a second lower-most portion of the bottom wall. The first convex surface and the second convex surface are integral with the first and second lower-most portions of the bottom wall, and the first and second concave wall surfaces are disposed between the first and second convex surfaces.

For the purpose of this disclosure, geometric terms such as "circle", "sphere", "oval," and the like are used as references and for clarity of understanding, as would be understood by one of ordinary skill in the art. Accordingly, these terms should not be limited to strict Euclidean standards.

BRIEF DESCRIPTION OF THE DRAWINGS

30 In the drawings:
35 FIG. 1 is a perspective view of a portion of an armored cab, for a vehicle, such as a tactical vehicle or truck;
40 FIG. 2 is another perspective view of the armored cab of FIG. 1 looking upwardly;
45 FIG. 3 is a front view of the cab of FIGS. 1 and 2;
50 FIG. 4 is a side view of the cab of FIGS. 1-3;
55 FIG. 5 is a front view of another embodiment of a portion of an armored cab, for a vehicle, such as a tactical vehicle or truck; and
60 FIG. 6 is a side view of the cab of FIG. 5.
While the invention will be described in connection with the certain embodiments, it will be understood that it is not intended to limit the invention to those embodiments. On the contrary, it is intended to cover all alternatives, modifications, and equivalents, as may be included within the spirit and scope of the invention as defined by the appended claims.

DETAILED DESCRIPTION OF SPECIFIC EMBODIMENTS

With reference to FIGS. 1-4, a portion of a cab, or armored cab, **70** for use with a vehicle, such as a JLTV, tactical vehicle, truck (not completely shown), combat vehicle, cargo truck, or troop transport vehicle is shown. The cab, or armored cab, **70** generally includes: at least one upper wall, or upper wall surface, **72**; preferably at least two side walls, or side wall surfaces, **73**; at least one front wall, or front wall surfaces, **74**; at least one back wall, or back wall surfaces, **75**; and at least one floor, or bottom wall, or bottom wall surface, **76**. The upper wall **72** may be provided with an opening **77** for a gun turret (not shown). At least one, and preferably two, doors **78** (shown in FIG. 4) may be provided in openings **78'** in the side walls **73**. The front wall surfaces **74** may be provided with at least one, and preferably two, windows **80**. Preferably, the windows **80** are made from any suitable bullet-proof material which is transparent and affords the desired visibility for the

occupants (not shown) of the armored cab **70**, while at the same time affording protection against the explosive forces previously described.

Still with reference to FIGS. 1-4, the armored cab 70 is manufactured from materials having the requisite strength characteristics to withstand the explosive forces previously described. At least some, and preferably all, of the walls 72, 73, 74, 75, and 76 of armored cab 70, and doors 78 are made from an armor plate material, which is known as high hard steel, or armor steel, or other similar material having the requisite strength characteristics to withstand the forces encountered in a battlefield, or other type of conflict situation. Alternatively, the armor plate material may be affixed to, or riveted (using rivets 79) to, at least some, and preferably all, of the walls 72, 73, 74, 75, and 76 of armored cab 70, and doors 78. Preferably, to provide protection to the occupants of armored cab 70 against IEDs, land mine strikes, and similar explosions from beneath armored cab 70, or bottom wall surface 76 of armored cab 70 may include at least one concave surface 90.

Preferably, the at least one concave surface 90 is of a smooth concave shape, and thus forms an inwardly hollow rounded arch. In an embodiment, the concave surface 90 includes at least one concave wall surface 91, and is generally disposed, along a length of the cab 70, in a direction substantially parallel with the longitudinal axis 92 of cab 70. Alternatively, as shown in FIG. 3, the concave surface 90 includes a forward concave wall surface 91', and a reward concave wall surface 91. Preferably, the concave surface 90 extends substantially the entire length of the cab 70. Preferably the forward concave wall surface 91', and the reward concave wall surface 91 extend, or face, downwardly toward the ground, or roadway (not shown), and away from the cab 70. The at least one concave surface 90, the forward concave wall surface 91', and the reward concave wall surface 91, may take any arched concave shape, including spherical, oval, egg, conical, cylindrical, and the like shapes. Accordingly, the at least one concave surface 90, the forward concave wall surface 91', and the reward concave wall surface 91, may have a curvature equal to the curvature of the surface of a sphere having one particular radius. Alternatively, the surface of at least one concave surface 90, the forward concave wall surface 91', and the reward concave wall surface 91, may have a curvature equal to the curvature of the surface of an oval having two different radii.

The at least one concave surface 90 is preferably disposed substantially parallel to the longitudinal axis 92 of cab 70, and disposed substantially intermediate the side walls 73 of cab 70. In an embodiment, the at least one concave surface 90 is disposed centrally between the side walls 73, and substantially parallel to the longitudinal axis 92 of the cab 70. The at least one concave surface 90 may be disposed beneath a portion of the floor 100 of the cab 70. Alternatively, as shown in FIG. 3, a first concave wall surface 91, is disposed beneath a forward, or front portion of the floor 100 of the cab 70, and a second concave wall surface 91, is disposed beneath a rearward, or rear, portion of the floor 100 of the cab 70. The first concave wall surface 91 and the second concave wall surface 91 are preferably disposed substantially parallel with respect to each other, substantially parallel to the longitudinal axis 92 of cab 70, and substantially intermediate the side walls 73 of cab 70. In an embodiment, the at least one concave surface 90 forms the transmission tunnel of a vehicle such as a JLTV, and the like tactical vehicles.

In the illustrated embodiment of FIGS. 1-6, the concave surface 90 comprises a downwardly facing portion of a cylinder, for example approximately or about a semi-cylinder.

The cylinder portion has a longitudinal axis **93**. The longitudinal axis **93** of the cylinder portion lies substantially in a common vertical plane with the longitudinal axis **92** of the cab **70**, and is angled slightly relative to a horizontal plane **5** containing the longitudinal axis **92** of the cab **70**. The cylinder portion has a forward end **95** and a rearward end **97**. The cylinder portion is inclined such that an upper edge of the forward end **95** is positioned above an upper edge of the rearward end **97**. The cylinder portion has a radius R . At the forward end **95** of the cylinder portion, the radius R is swung from a point **PF**, and at the rearward end **97** of the cylinder portion, the radius R is swung from a point **PR**. Both points **PF** **10** and **PR** are located above a lowermost edge of the cab **70**.

In the event of a mine blast or explosion of an IED beneath 15 cab 70, the concave surface 90 contains and manages, or mitigates, the blast effects from the explosion. The concave surface 90 affords cab 70, and in particular the bottom wall surface 76, with increased structural strength which reduces dynamic and permanent deformation of the bottom wall surface 76 of the cab 70. Blast resistance is further enhanced 20 from the strength of the armor plate material utilized for concave surface 90. If desired, the at least one concave surface 90, and/or concave wall surface 91 may be provided with locally applied stiffening ribs (not shown). Blast resistance 25 may be further improved with generally known and specialized welding, as well as joint re-enforcement techniques.

With reference to FIGS. 1-4, armored cab 70 may include flat panels, 105 which are angularly disposed with respect to each other which also form a portion of the bottom wall surfaces 76 of cab 70. These panels assist to deflect the previously described explosive blasts.

Turning now to FIGS. 5 and 6, another embodiment of a portion of an armored cab 70' is illustrated. In this embodiment, armored cab 70' not only includes at least one concave surface 90, as previously described, but also includes at least one convex surface 110. The at least one convex surface 110 preferably forms a portion of the bottom wall surface 76. The at least one convex surface 110 may take any arched convex shape, including spherical, oval, egg, conical, cylindrical, elliptical, and the like shapes. Accordingly, the surface of the at least one convex surface 110 and the at least one convex wall surface 111 may have a curvature equal to the curvature of the surface of a sphere having one particular radius. Alternatively, the surface of the at least one convex surface 110 and the at least one convex wall surface 111 may have a curvature equal to the curvature of the surface of a oval having two different radii. In an embodiment, the convex surface 110 and the at least one convex wall surface 111 have a smooth shape. In an embodiment, the at least one convex surface 110 includes at least one convex wall surface 111, which extends, along a length of the cab 70, in a direction substantially parallel to the longitudinal axis 92 of cab 70', along the lower-most portion of bottom wall surfaces 76. The convex wall surface 111 may face toward the cab 70'.

55 In a preferred embodiment, there are two convex wall surfaces **111**, each extending substantially parallel to the longitudinal axis **92** of cab **70'**, along the lower-most portion of bottom wall surfaces **76**. Preferably, each of the convex wall surfaces **111** extend substantially the entire length of the cab **70'**. Each of the two convex wall surfaces **111** are preferably tangent with its respective flat panel **105**, which is tangent with its respective side wall **73**. In this embodiment, the first convex wall surface **111** is disposed beneath and exterior to the at least one concave surface **90** on a first side of the at least one concave surface **90**, and the second convex wall surface **111** is disposed beneath and exterior to the at least one concave surface **90** on a second side of the concave surface **90**.

Preferably, the first and second sides of the at least one concave surface 90 oppose one another. In this manner, the at least one concave surface 90 is disposed between the first and second convex wall surfaces 111. These convex surfaces 110, or convex wall surfaces 111, provide blast resistance against explosive forces resulting from mine blasts and IED explosions. The structural strength from the convex surfaces 110, or convex wall surfaces 111, help reduce dynamic and permanent deformation of the bottom wall surfaces 76 of cab 70 upon encountering explosive forces. The convex surfaces 110, or convex wall surfaces 111, may be provided, if desired, with locally applied stiffening ribs (not shown). Blast resistance may be further improved with generally known and specialized welding, as well as joint re-enforcement techniques.

Specific embodiments of the present invention have been described and illustrated. It will be understood to those skilled in the art that changes and modifications may be made without departing from the spirit and scope of the inventions to be defined by the appended claims.

We claim:

1. For a vehicle armored cab having a longitudinal axis, an armored cab bottom wall comprising:

a centrally disposed downwardly facing concave wall forming a power train tunnel of the cab and extending generally parallel to the longitudinal axis of the cab, and a pair of opposite laterally disposed outboard walls extending generally parallel to the longitudinal axis of the cab, said concave wall having a smoothly curved upper portion and a pair of opposite laterally disposed lower portions extending downwardly and laterally outwardly relative to said upper portion,

each of said outboard walls extending downwardly and laterally inwardly relative to a respective one of said lower portions of said concave wall and defining, with said respective lower portion, a lowermost portion of said bottom wall on each lateral side of the longitudinal axis of the cab,

each said lowermost portion of said bottom wall thereby configured to present a significantly reduced downwardly facing surface area perpendicular to an upwardly directed blast beneath said lowermost portion.

2. The armored cab bottom wall of claim 1 wherein each of said pair of outboard walls includes a planar portion.

3. The armored cab bottom wall of claim 1 wherein each of said pair of outboard walls includes a convex portion.

4. The armored cab bottom wall of claim 1 wherein each of said pair of outboard walls includes a planar portion and a convex portion.

5. The armored cab bottom wall of claim 4 wherein said convex portion is positioned below and laterally inward of said planar portion.

6. The armored cab bottom wall of claim 1 wherein said concave wall includes a portion of a cylinder.

7. The armored cab bottom wall of claim 6 wherein said cylinder has a longitudinal axis, the longitudinal axis of said cylinder lying substantially in a common vertical plane with the longitudinal axis of the cab, the longitudinal axis of said cylinder angled relative to a horizontal plane containing the longitudinal axis of the cab.

8. The armored cab bottom wall of claim 7 wherein said cylinder has a forward end and a rearward end, and wherein said cylinder is inclined such that an upper edge of said forward end is positioned above an upper edge of said rearward end.

9. The armored cab bottom wall of claim 6 wherein said cylinder has a radius, the radius being swung from a center point located above a lowermost edge of the cab.

10. The armored cab bottom wall of claim 1 wherein said bottom wall further includes a front end wall and a rear end wall, said front end wall substantially perpendicular to the longitudinal axis of the cab, said rear end wall angled relative to the longitudinal axis of the cab such that a lower edge of said rear end wall is located forward of an upper edge of said rear end wall.

11. The armored cab bottom wall of claim 10 wherein said front end wall and said rear end wall are planar.

12. The armored cab bottom wall of claim 1 wherein said bottom wall is fabricated of an armor plate material selected from the group consisting of high hard steel and armor steel.

13. The armored cab bottom wall of claim 1 wherein said bottom wall extends for a substantial portion of the length of the cab.

14. For a vehicle armored cab having a longitudinal axis, an armored cab bottom wall comprising:

a centrally disposed downwardly facing concave wall forming a power train tunnel of the cab and extending generally parallel to the longitudinal axis of the cab, and a pair of opposite laterally disposed outboard walls extending generally parallel to the longitudinal axis of the cab, said concave wall having a smoothly curved upper portion and a pair of opposite laterally disposed lower portions extending downwardly and laterally outwardly relative to said upper portion,

each of said outboard walls extending downwardly and laterally inwardly relative to a respective one of said lower portions of said concave wall and defining, with said respective lower portion, a lowermost portion of said bottom wall on each lateral side of the longitudinal axis of the cab,

each said lowermost portion of said bottom wall thereby configured to minimize a downwardly facing surface area perpendicular to an upwardly directed blast beneath said lowermost portion.

15. The armored cab bottom wall of claim 14 wherein each of said pair of outboard walls includes a planar portion.

16. The armored cab bottom wall of claim 14 wherein each of said pair of outboard walls includes a convex portion.

17. The armored cab bottom wall of claim 14 wherein each of said pair of outboard walls includes a planar portion and a convex portion.

18. The armored cab bottom wall of claim 17 wherein said convex portion is positioned below and laterally inward of said planar portion.

19. The armored cab bottom wall of claim 14 wherein said concave wall includes a portion of a cylinder.

20. The armored cab bottom wall of claim 19 wherein said cylinder has a longitudinal axis, the longitudinal axis of said cylinder lying substantially in a common vertical plane with the longitudinal axis of the cab, the longitudinal axis of said cylinder angled relative to a horizontal plane containing the longitudinal axis of the cab.

21. The armored cab bottom wall of claim 20 wherein said cylinder has a forward end and a rearward end, and wherein said cylinder is inclined such that an upper edge of said forward end is positioned above an upper edge of said rearward end.

22. The armored cab bottom wall of claim 19 wherein said cylinder has a radius, the radius being swung from a center point located above a lowermost edge of the cab.

23. The armored cab bottom wall of claim 14 wherein said bottom wall further includes a front end wall and a rear end

wall, said front end wall substantially perpendicular to the longitudinal axis of the cab, said rear end wall angled relative to the longitudinal axis of the cab such that a lower edge of said rear end wall is located forward of an upper edge of said rear end wall. 5

24. The armored cab bottom wall of claim **23** wherein said front end wall and said rear end wall are planar.

25. The armored cab bottom wall of claim **14** wherein said bottom wall is fabricated of an armor plate material selected from the group consisting of high hard steel and armor steel. 10

26. The armored cab bottom wall of claim **14** wherein said bottom wall extends for a substantial portion of the length of the cab.
